(57) **CLAIM**

The ornamental design for a hub and lever, as shown and described.

DESCRIPTION

FIG. 1 is a left front perspective view of a hub and lever showing my new design;

FIG. 2 is a left side view thereof;

FIG. 3 is a right side view thereof;

FIG. 4 is a top view thereof;

FIG. 5 is a bottom view thereof;

FIG. 6 is a front view thereof; and,

FIG. 7 is a rear view thereof.

The broken line showing of the small horizontal gap in FIGS. 1-3, 6 and 7 and of the unshaded circular region in FIG. 5 represents an unclaimed area and forms no part of the claimed design.
